Patented July 28, 1925.

UNITED STATES PATENT OFFICE.

FAUSTINO SOTOMAYOR, OF SALINAS, PORTO RICO.

EXERCISING APPARATUS.

Application filed April 14, 1924. Serial No. 706,518.

To all whom it may concern:

Be it known that I, FAUSTINO SOTOMAYOR, citizen of the United States, residing at Salinas, in the Department of Guayama, Porto Rico, have invented certain new and useful 5 Improvements in an Exercising Apparatus, of which the following is a specification.

This invention relates to exercising apparatus, and it consists in the novel features 10 hereinafter described and claimed.

An object of the invention is to provide an apparatus of the character stated having its parts so arranged and assembled that they may be shifted or adjusted whereby 15 more or less effort will be required in the use of the apparatus, thus making it possible to vary the exercises, and by shifting or adjusting the parts and features of a single apparatus. The apparatus is of that form 20 or type which is generally known as a "chest weight" and the path of movement of the weight may be disposed from a vertical position to a position inclined at any angle within the radius of an arc of 90 degrees.

With the above objects in view the apparatus includes a vertically fixed standard having an arm pivotally mounted at the lower portion thereof, a segment is connected at its upper portion with the said 25 standard and at its lower end with the same support upon which the standard is mounted. The segment describes an arc of 90 degrees and is provided at its under side with a set of ratchet teeth. The arm is provided 30 with a catch which may be engaged in the teeth whereby the said arm may be disposed at any desired position between the standard and the support upon which it is mounted. The second standard is vertically mounted 35 beyond the end of the segment and a pulley 40 carrier is adjustably mounted thereon. A weight is slidably mounted upon the arm and a flexible element is connected at one end with the weight trained over the end of 45 the arm and under the pulley which is mounted upon the second mentioned standard.

In the accompanying drawings:—

Figure 1 is a side elevation of the exercising apparatus.

Figure 2 is a top plan view of the same.

Figure 3 is an enlarged detail transverse sectional view thereof cut on the line 3—3 of Figure 1.

Figure 4 is a transverse sectional view of the arm cut on the line 4—4 of Figure 1.

Figure 5 is a fragmentary longitudinal view of the inner end of the arm of the apparatus.

Figure 6 is a similar view of the outer 60 end portion of the arm of the apparatus.

The exercising apparatus comprises a vertically positioned standard 1 which may be a single piece or which may be composed of spaced uprights. An arm 2 is pivotally 65 connected at its lower end with the lower portion of the standard 1 and carries at its lower end a spring pressed bumper block 3. The arm 2 is preferably made of channel iron, although it may be made of any 70 other shape or any other material. A weight 4 is slidably mounted upon the arm 2 and is provided with edge flanges 5 which engage around the sides of the said arm as best shown in Figure 4 of the drawings. A segment 5 is connected at its upper end with the standard 1 and at its lower end with the floor or the same support upon which the standard 1 is mounted. The segment 5 is provided at its under side with a set of 75 ratchet teeth 6. The segment 5 may be composed of two sections which are spaced from each other or a single section which is slotted longitudinally as preferred. A bolt 7 is slidably mounted at the outer free end 80 of the arm 2 and may engage the teeth 6 whereby the arm 2 may be held at a desired angle with relation to the horizontal line. A guide roller 8 is mounted upon the outer free end of the arm 2 and a chain 9 is 85 trained over the said guide roller. The inner end of the chain 9 is connected with the weight 4. Spaced standards 10 are mounted at the outer end of the segment 5 and are 90 vertically disposed. These standards are 95 provided along their vertical heights with series of spaced openings 11 adapted to receive pins 12. Sleeves 13 are slidably mounted upon the standards 10 and the pins 12 pass through the said sleeves and enter 100 the openings 11 whereby the sleeves are held in vertically adjusted positions upon the said standards 10. The sleeves 13 are connected together by a transversely disposed bearing 14 which receive the ends of a shaft 16, the said shaft having a sprocket wheel 15 mounted thereon. The chain 9 hereinbefore described is trained under the sprocket wheel 15 and carries at its outer end a handle bar 17.

From the above description taken in conjunction with the accompanying drawings it

will be seen that an exercising apparatus is provided wherein the arm 2 thereof may be readily positioned at any desired angle with relation to a horizontal line and that when the handle bar 17 is grasped by one who is exercising and the chain 9 is moved longitudinally, the weight 4 will reciprocate back and forth along the bar 2. According to the angle of disposition of the bar 2 with relation to a horizontal line the effort to carry on the exercise will vary, that is to say a greater effort will be required to carry on the exercise if the arm 2 is vertically disposed than would be necessary if the said arm 2 is disposed at an acute angle with relation to a horizontal line.

Having thus described the invention, what I claim is:—

1. An exercising apparatus comprising a vertically positioned standard, a segment connected with the standard and with the support upon which the standard is mounted and provided at its under side with ratchet teeth, an arm pivotally mounted at the lower portion of the standard, means carried by the arm for engaging the teeth of the segment, a weight slidably mounted upon the arm, a guide pulley journaled at the upper end portion of the arm and a flexible element connected with the weight trained over the guide pulley.

2. An exercising apparatus comprising a vertically disposed standard, a segment connected with said standard, an arm pivoted to the standard, means for adjustably securing the free end portion of the arm to the segment, a weight slidably mounted upon the arm, a pulley journaled at the free end

portion of the arm, and a flexible element trained over the pulley and connected with the weight.

3. An exercising apparatus comprising a vertically disposed standard, a segment connected with the standard, an arm pivoted to the standard, means for adjustably securing the arm to the segment, a bumper block located at the lower portion of the arm, a weight slidably mounted upon the arm, a guide pulley journaled at the free end portion of the arm, and a flexible element trained over the pulley and connected with the weight.

4. An exercising apparatus comprising a vertically disposed standard, a segment connected therewith, an arm pivotally connected with the standard, means for adjustably securing the free end portion of the arm to the segment, a weight slidably mounted upon the arm, a guide pulley journaled at the free end portion of the arm, a standard erected beyond the segment, a pulley adjustably mounted upon the last mentioned standard, and a flexible element trained under the last mentioned pulley, over the first mentioned pulley and connected with the weight.

5. An exercising apparatus comprising a standard, a segment connected with said standard, an arm pivoted to the standard and adjustably engaging said segment, a weight slidably mounted upon the arm, and a flexible element movable along said arm and connected to said weight.

In testimony whereof I affix my signature.

FAUSTINO SOTOMAYOR.
